US0D1009159S

(12) **United States Design Patent** (10) **Patent No.:** **US D1,009,159 S**
(45) **Date of Patent:** **** Dec. 26, 2023**

(54) **CLIP TAG**

(71) Applicant: **Bedford Industries, Inc.**, Worthington, MN (US)

(72) Inventors: **Jay Milbrandt**, Worthington, MN (US); **Jaden Balster**, Adrian, MN (US); **Eric Milbrath**, Brewster, MN (US); **Evan Place**, Worthington, MN (US); **Trevor Wintz**, Round Lake, MN (US)

(73) Assignee: **Bedford Industries, Inc.**, Worthington, MN (US)

(**) Term: **15 Years**

(21) Appl. No.: **29/759,408**

(22) Filed: **Nov. 23, 2020**

Related U.S. Application Data

(62) Division of application No. 29/641,677, filed on Mar. 23, 2018, now Pat. No. Des. 924,976.

CLAIM

The ornamental design for a clip tag, as shown and described.

DESCRIPTION

FIG. 1 is a perspective view of a first embodiment thereof; FIG. 2 is a front view thereof;

FIG. 3 is a right side view thereof;

FIG. 4 is an enlarged view of the area 4 shown in FIG. 3;

FIG. 5 is a left side view thereof;

FIG. 6 is a top view thereof;

FIG. 7 is a bottom view thereof;

FIG. 8 is a rear view thereof;

FIG. 9 is a perspective view of a second embodiment thereof;

FIG. 10 is a front view thereof;

FIG. 11 is a right side view thereof;

FIG. 12 is an enlarged view of the area 12 shown in FIG. 11;

FIG. 13 is a left side view thereof;

FIG. 14 is a top view thereof;

FIG. 15 is a bottom view thereof; and,

FIG. 16 is a rear view thereof.

The evenly spaced dash lines depict environment that is unclaimed. The dot-dash-dot lines themselves form no part of the claimed invention.

1 Claim, 8 Drawing Sheets
